United States Patent Office

Des. 179,051
Patented Oct. 30, 1956

179,051

CHAIR FRAME

Joseph A. Ashkouti, Atlanta, Ga.

Application March 9, 1954, Serial No. 29,440

Term of patent 7 years

(Cl. D15—1)

The figure is a perspective view of a chair frame showing my new design.

The dominant features of the design reside in the portions shown in full lines.

I claim:

The ornamental design for a chair frame, as shown and described.
